ELEVATOR SAFETY DEVICE

Bjarne Henricksen, North Bergen, N. J., assignor
to Sedgwick Machine Works, Incorporated,
Poughkeepsie, N. Y., a corporation of New
York

Application December 30, 1936, Serial No. 118,192

8 Claims. (Cl. 187—48)

This invention relates to safety devices for elevator constructions and more particularly to combined door-locking and circuit-controlling devices adapted especially for use in connection with dumbwaiters.

An object of the invention is to provide mechanism associated with a vertically moving car, and with a door, for locking the door in closed position at all times while the car is not in alignment with the door opening.

Another object of the invention is to provide mechanism whereby the energizing circuit, controlling movement of the car, is held closed while the door is locked and is held open while the door is unlocked and is in open position relative to the car.

Another object of the invention is to provide a housing for control mechanism adapted to be secured to the jamb of a door and which contains mechanism operated both by the door and by the car in the shaft associated with the door.

A further object of the invention is to provide safety devices of the foregoing character so constructed as to require a small space for installation, and so constructed that a minimum of moving and stationary parts are required whereby the advantages of utility and space saving are obtained.

In carrying out the foregoing and other objects of the invention, use is made of a housing which can be secured to a door jamb preferably either at the top or the bottom thereof. Connected to the housing in some suitable fashion is an arm to be contacted by a control cam on the vertically moving car in the shaft, which arm has a locking member associated therewith. This locking member is adapted to be engaged by a keeper attached to the shaft door so that in one position of the locking member the keeper prevents movement of the door and in the other position of the locking member the keeper is released so that the door can be opened. Also associated with the locking mechanism is a circuit-control device so operated that when the door is in closed position and locked the circuit is closed so that the car can be operated in the shaft. When the door, however, is opened, the circuit is broken so that energy cannot be supplied to the car-moving mechanism, with the result that the car cannot be energized to move until all doors associated with the shaft thereof are closed.

In one form of the invention the locking mechanism is of a form especially adaptable for use in connection with hinged doors. In this form

the keeper fastened to the door has a hook member adapted to enter a housing secured to the jamb and engage a locking crank member therein. The crank member is actuated by an arm, one end of which engages a cam on the vertically moving car. Secured also within the casing are two contact members which are adapted to be bridged by a conductor extending thereacross when the latch is locked by the crank locking member. The parts comprising the contact members and the bridge are so related that a circuit closing relation occurs only when the door is fully closed and, moreover, these parts are so related that they move to circuit closing position with a wiping action which assures a good electrical connection and eliminates the necessity for cleaning the contacts at any time.

In another form of the invention especially adaptable for use in connection with vertically sliding doors the casing to be secured to the jamb or adjacent thereto has an arm extending beyond one edge of the casing. One of the sliding doors (if there be a pair thereof) has a keeper secured thereto which is movable into position to be engaged by the locking arm when the door or doors are closed. In addition, the casing has within the interior thereof a relatively fixed contact and a movable contact, the latter being provided with an actuator which is engaged by the door keeper to move the movable contact to circuit-closing position when the door is in locked position. Again, the circuit closing parts are so related that the energizing circuit is closed only when the door is fully shut and also provision is made for causing a wiping movement of the contacts to eliminate the necessity for any cleaning thereof.

Other features, objects and advantages of the invention will become apparent by reference to the following detailed description of the accompanying drawings illustrating the same, wherein

Fig. 1 is a vertical section of a portion of a shaft with the invention applied thereto;

Fig. 2 is a vertical section taken substantially on the line 2—2 of Fig. 1;

Fig. 3 is an enlarged face view of the keeper plate used in the present invention;

Fig. 4 is a section taken substantially on the line 4—4 of Fig. 3;

Fig. 5 is a central vertical section of the jamb casing of the present invention;

Fig. 6 is a section taken substantially on the line 6—6 of Fig. 5;

Fig. 7 is a side elevation of a modification of the invention;

Fig. 8 is a vertical section of the same mechanism in conjunction with a keeper;

5 Fig. 9 is a section taken substantially on the line 9—9 of Fig. 8;

Fig. 10 is a fragmentary showing of the arrangement of Fig. 8 with the contacts in open position; and

10 Fig. 11 is a fragmentary showing of a safety feature of the arrangement shown in Fig. 7.

Referring now to the drawings and particularly to Fig. 1, 16 indicates generally a shaft for a dumbwaiter or other vertically moving car 11, 15 such car being shown only in outline and in fragmentary construction. The shaft 10 is provided with a door opening 12 closed by a door 14 hinged at 15 to one edge of the shaft opening. Secured to the jamb of the opening in some convenient 20 position is a housing indicated generally at 16, and secured to the door 14 is a keeper plate indicated generally at 17 positioned to be brought in alignment with the housing 16.

The keeper mechanism in addition to plate 17 25 comprises a lock member 18 having a hook 19 at the end thereof. This lock member may be formed integrally with the plate or may be secured thereto in any desired fashion. Extending from plate 17 is a sleeve 20 of some suitable insulating material, such sleeve being hollowed out and threaded for the reception of a bolt 21. A nut 22 on the bolt serves to locate the bolt longitudinally relative to the sleeve. The plate 17 is provided with a plurality of apertures 24 for the 30 passage of screws or other fastening means for securing the plate to the door 14.

The housing indicated generally at 16 comprises 35 a rectangular shell 30 made of some suitable metal with the opposite sides thereof adapted to be closed by plates 31. The corners of the shell 30 are internally enlarged so that threaded apertures 32 may be provided in diagonally opposite corners and through apertures 34 in the other corners. The threaded apertures 32 serve to receive screws by which the plates 31 are locked in 40 position. The apertures 34 are provided for the passage of lag screws or other fastening means utilized for securing the housing to the door jamb; it being understood of course that the plates 31 have apertures in register with the openings 34.

Extending inwardly from one wall of the shell 30 are separated ears 35 provided with aligned apertures 36. A crank 37 is pivotally mounted 45 between these ears 35 on a shaft 38 passing through the apertures 36. One arm of crank 37 extends through an opening 39 in the casing wall and terminates at an enlarged head 40. The other arm of the crank 37 is provided with a hook terminal 41 which is located within the casing. 50 A spring 42 has one end resting on a boss 44 extending inwardly from one shell wall and the other end resting on one arm of the crank 37. Suitable means such as short studs 45 are provided for retaining the spring in proper position. 55 This spring serves to maintain the crank 37 in the position shown in Fig. 5. Secured to the arm of crank 37 which extends through the casing is a bar 50 on the upper end of which is rotatably mounted a roller 51. The method of attaching the bar 50 to the head 40 of the crank arm is shown clearly in Fig. 6. Use is made of a short bar 52 having an angular extension 54 of a length corresponding to the thickness of the head 40. The bar 50 and the short bar 52 are provided with 60 aligned apertures, and the head 40 is also pro-

vided with an aperture to be aligned with the end-most apertures in the two bars. Bolts 55 passing through the aligned apertures have nuts 56 threadedly engaged on the ends thereof. By relieving the pressure supplied by these nuts 56 it is possible to adjust the angular relation between the bar of crank 37 and the bar 50 to any desired degree.

The car 11 which is mounted for vertical movement of the shaft is provided with a cam 57 of 10 some conventional character, which cam is so disposed that its path of travel concurrently with the car will cause the cam to contact with the roller 51 when the car is properly positioned relative to the opening 12. Any desired arrangement 15 of cam may be utilized.

Secured to the wall of the shell 30 beneath the ears 35 is a block 60 of some suitable insulating material. This block is fastened in place by means of screws 61. A thin sheet of insulating material 62 is positioned between the wall of the casing and the block 60 and is provided with four strips fitting adjacent the four edges of the block 60, such strips being shown at 64. Secured to one side of block 60 is a plate 65 of some good electric conducting material, such plate being secured to the block by screws 66. This plate has a tongue 67 extending beyond the inner edge of block 60 and has an angular portion 68 extending over the inner edge of the block 60. The angular part 68 is threaded for the reception of a terminal screw 69. A similar plate 70 is secured in the same fashion to the other side of the block 60 in staggered relation to the plate 65, and the plate 70 has a corresponding part providing a terminal screw 71. Electric conductors 72 and 74 can pass through an opening 75 in the casing wall to be connected respectively to the terminal screws 69 and 71.

One wall of the casing 30 is provided with an opening 76 and a second opening 77. These openings are so spaced that their centers are separated a distance corresponding to the distance between the centers of the hook member 18 and the insulating sleeve 20 carrying the conducting bridge 21.

The operation and use of this construction is substantially as follows: The housing 16 is secured to the door jamb either near the top thereof or near the bottom thereof or at any other suitable location. The keeper member 17 is then secured to the door 14 in such position that the lock 18 and the bridge 21 can be moved into alignment with the openings 76 and 77 respectively. When the parts have been so secured to their respective mountings, the bar 50 may be properly adjusted, such adjustment preferably being made while a car 11 is in proper register with the door opening 12. Such adjustment is made when the roller 51 is in contact with cam 57 so that under these conditions the crank 37 is rotated until the hook part 41 thereof is below the path of travel of the hook part 19 of lock 18. Under these conditions, it is possible to move the door 14 freely. When the adjustment has been made the bar 50 is locked in position by tightening the respective nuts 56.

With this construction let it be assumed that a car is at rest at the proper landing. The door 14 is free to be open since, as before stated, the cam 57 causes the bar 50 and the crank 37 secured thereto to be rotated about the shaft 38 until the hook 19 is released by the hook 41. When the door is open the two contacts 67 and 67' are not bridged so that a car energizing circuit associated 75

therewith cannot be closed to cause movement of the car in the shaft. As soon as the door is closed, however, the lock 18 intrudes into the casing 30 and the head of the bolt 21 bridges the contacts 67 and 67' thereby closing a circuit including the conductors 72 and 74. The contacts 67 and 67' and the bridge formed by the head of bolt 21 are so arranged that the respective parts engage with a wiping action which serves to remove any dust or other foreign matter and to thereby maintain the electrical contacts in clean condition. These conductors 72 and 74 are associated in some manner with the control circuit for the car. This control circuit can then be energized by some switch arrangement (not shown and of conventional character) to cause the car to move away from the particular landing under discussion. As soon as the car has moved away from this landing the bar 50 is moved about its pivotal point by the spring 42, such movement being permitted by the removal of the cam 51. Such movement causes the hook 41 to move upwardly into the path of the hook 19 so that attempted opening of the door causes an engagement of these respective hook parts effectively preventing opening of the door. From this it follows that while the door is in closed position the contacts associated with the car energizing circuit are bridged so that the car can be moved freely in the shaft. Once the door has moved beyond a position in which the hook parts of the two locking members cannot be engaged, then these contacts are unbridged so that the circuit controlling movement of the car is deenergized. This arrangement provides a simple and efficient safety control for the car.

The embodiment of the invention illustrated in Figs. 7 to 11, inclusive, is adapted particularly for use in connection with installations wherein the opening in the shaft is closed by either a sliding single door or by a pair of sliding doors. In this form of the invention use is made of an elongated substantially rectangular shaped open-sided shell 80 of some suitable metal. The sides of the shell are closed by plates 81 having apertures therein for the passage of screws threaded into threaded apertures 82 in the casing. One edge of the casing has an extension 84, to the top part of which is pivotally secured a crank member 85 by means of a bolt 86 passing through the extension 84 and threadedly passing through an aperture in the crank 85. A nut 87 locks the parts together so that the crank is capable of rotation relative to the extension. Extending outwardly from the extension 84 are separated ears 88. These ears are positioned on each side of an arm 89 of the crank 85. This arm 89 is provided with a through threaded aperture 90 for the reception of a short screw plug 91 on one side thereof and for the reception of a coiled spring 92 on the other side thereof. The aperture 90 has the two longitudinal halves thereof so threaded that the plug 91 can be inserted from either end thereof. This plug 91 can be adjusted so that it will strike one of the ears 88 to limit movement of the crank towards such ear. The arm part 89 of crank 85 has a portion 93 thereof extending beyond one edge of the casing 80 and this portion 93 has the top part thereof provided with sloping edges as shown at 94. Secured to the upper end of the crank 85 is an arm mechanism similar to the arm 50 and accordingly the various parts have been given the same reference characters.

75. Pivots mounted partially within the casing

80 is a block 95, which block is capable of rotation to a limited extent on a shaft 96 mounted between opposite sides of the housing. A striker part 97 of this block 95 is located exterior of the casing and a suitable opening is provided in the casing wall for the passage of a part of the block from the position shown in Fig. 8 to that shown in Fig. 10. Depending from block 95 is a stud 98 of some suitable insulating material, such stud being provided with a cross slot 99, one wall of which is flared outwardly as shown in Fig. 8. A spring 95' acts to force the block to the Fig. 10 position.

A block of insulating material 100 is secured within the casing by means of screws 101. A thin sheet of insulating material has a portion thereof interposed between the block and the casing as shown at 102 with the remainder thereof foldable around the block to form a lining within the casing. Secured to the block at the upper edge thereof is an angle plate 104 of some good electric conducting material, such plate having a contact arm 105 extending upwardly therefrom and having a terminal screw 106 secured thereto. A second angle plate 107 of similar material has a bent contact arm 108 extending upwardly therefrom and a terminal screw 109 secured thereto. Conductors 110 and 111 which pass through an opening 112 in the bottom of the casing are connected respectively to the terminal screws 106 and 109. The contacts 105 and 108 possess some degree of resiliency for a purpose to be explained later. A boss 113 extending from the wall of the casing has an aperture 113, therethrough. Another aperture 114 is provided in the upper end of the casing. The two plates 81 are provided with holes to register with apertures 113' and 114 so that the complete housing can be secured to a door jamb.

The striker utilized in this form of the invention comprises a bar of metal, a portion 120 of which has been illustrated. This bar is adapted to be secured directly to a sliding door so that when the door is closed the bar will assume the position relative to the housing shown in Fig. 7. 45 The end of the bar extending beyond the edge of the door, which edge has been shown by broken lines 121, has a recess 122 cut therein and the lower edge of the bar is pointed as indicated at 124.

The operation and use of this form of the invention is substantially as follows: The housing is secured to a door jamb at some suitable point with the roller 51 on the end of bar 50 positioned to be engaged by a cam 57' secured to the vertically movable car. The keeper 120 is secured to a sliding door in such fashion that when the sliding door is closed the keeper assumes the position shown in Fig. 8. In this position the lower edge of the outer end of the keeper engages the part 97 of block 95 and forces the block about its pivotal point against the resistance of spring 95'. The upper end of spring contact 108 fits in the slot 99 of the stud 98 so that when the block 95 has been moved to its innermost position relative to the casing contact 108 is forced against contact 105 thereby closing a circuit associated with the conductors 110 and 111. The contacts 105 and 108 are of spring nature and of such length and dimensions that movement of contact 108 against contact 105 causes a flexing of the latter contact thereby providing a wiping action which serves to keep these members in clean condition.

When all doors have been properly closed it is possible for the car in the shaft to move thereby

relieving the crank 85 from the resistance furnished by spring 92 so that this crank is moved to the position shown in Fig. 7, wherein the latch member 93 is located directly above the keeper 120. Due to such relative positions between the latch 93 and the keeper 120, the door, the edge of which is shown at 121, cannot be moved more than a very slight amount so that the door cannot be opened while a car is in movement in the shaft or while it is not in register with the door opening. The space between the top of the keeper 120 and the latch 93 is such that even though these parts be in engagement, still the keeper is maintained in engagement with the actuator block 95 to hold the circuit closed in the manner before stated.

When a car has reached a point in register with the door opening, the roller 51 is engaged by cam 57' moving the crank 85 about its pivotal point against spring 92 until the latch 93 is out of obstructing position relative to keeper 120. The door to which the keeper is attached may then be moved vertically since the keeper will pass by the latch. Such movement of the door causes the keeper to release the block 95 so that spring 95' causes pivotal movement of this block to the position shown in Fig. 10, wherein the contacts 105 and 108 are separated, due to the resiliency of contact 108, thereby breaking the car control circuit.

Should the sliding door be moved to open position a slight amount adventitiously while the car is starting its movement away from the landing, and before the roller 51 is out of engagement with cam 57', the keeper 120 will be moved upwardly a slight amount. However, the parts are so proportioned that as the cam and roller are separated the spring 92 forces the crank 85 until stopped by plug 91 at which time the lower edge of the latch 93 will fit in the recess 122 in the end of the keeper. This position is shown in Fig. 11. The consequence of such action is to break the energizing circuit established by the contacts 105 and 108 and at the same time the door is locked against further opening movement. The car naturally will be stopped at some point in the shaft and cannot be moved until the open-door condition has been rectified. Thus, the arrangement assures that the door will be in substantially closed position before the car can move in the shaft. This arrangement of double stops for the doors serves to positively prevent the insertion of any part of an operator's body into the shaft, thereby positively lessening the chances of accidents.

From the foregoing it will be seen that the present invention in either illustrated form provides arrangements whereby the factor of safety in the operation of motor-driven vertically moving cars within the shafts is materially increased. In either form of the invention the housing can be secured to either side of the door jamb to accommodate in one instance a door hinged at either side of the shaft, and can be located at the top or the bottom of the door opening and can be so positioned that the bar 50 extends either upwardly or downwardly as conditions may require. Since the two sides of the respective housings are of similar shape and formation it follows that the housings may be attached with either side against a supporting structure and due to the adjustment of the bars 50 relative to their respective cranks, it follows that these bars may extend either to the right or the left respective to the casings. Thus, the devices are adjustable to meet

any conditions which may arise in different installations. The arrangement whereby the positions of plug 91 and spring 92 are interchangeable permits the arm 85 to be held in locking position by the spring in either of the two positions. The present invention in either form is of such construction that a minimum of parts are required due to the simplicity of design and hence the devices can be made at a relatively small cost. At the same time, the devices are of the utmost efficiency and serve admirably in all respects.

It is to be understood that the invention can be modified beyond the embodiments illustrated herein, in view of which any limitations imposed thereupon are to be such only as are defined in the following claims.

I claim:

1. The combination, with a power driven car in a vertical shaft and with door-closed landings in said shaft, of vertically sliding doors for said landings, a housing adapted to be fastened to a door jamb, spaced spring contacts within said housing, a contact actuator pivoted in said housing and having a part extending therefrom, a crank pivotally secured exteriorly to said housing, and a keeper plate secured to a door fixed immovable relative thereto and movable with the door into position to engage said contact actuator and to underlie a portion of said crank.

2. The combination, with a power driven car in a vertical shaft and with door-closed landings in said shaft, said car having a cam thereon, of vertically sliding doors for said landings, a housing adapted to be fastened to a door jamb, spaced spring contacts within said housing, a contact actuator pivoted in said housing and having a part extending therefrom, a crank pivotally secured exteriorly to said housing and having an adjustable arm extending into said shaft, a cam engaging member on the end of said arm, and a keeper plate fixed to a door immovable relative thereto and movable with the door into position to engage said contact actuator and to underlie a portion of said crank.

3. The combination of a housing adapted to be fastened to a door jamb of an elevator shaft, spaced spring contacts within said housing, a contact actuator pivoted in said housing and having a part extending therefrom, a crank pivotally secured exteriorly to said housing, an extension arm adjustably secured to said crank to extend into said shaft, and a keeper plate adapted to be secured to a vertically sliding door in fixed immovable relation thereto and to be movable with the door into position to engage said contact actuator and to underlie a portion of said crank.

4. The combination of a housing adapted to be fastened to a door jamb of an elevator shaft, contacts within said housing, a contact actuator pivoted in said housing and having a part extending therefrom, a lever pivotally secured to said housing and lying entirely exteriorly thereof, an extension arm secured to said lever to extend into said shaft, a keeper member adapted to be secured to a sliding door in fixed immovable relation thereto, said lever being biased to cause a part thereof to extend into the path of movement of said keeper, said keeper being movable into position to engage said contact actuator to close said contacts and to lie behind a part of said lever whereby such part of the lever prevents sliding movement of the keeper in one direction.

5. The combination of a housing adapted to be fastened to a door jamb of an elevator shaft,

- contacts within said housing, a contact actuator pivoted in said housing and having a part extending therefrom, a lever pivotally secured to said housing and lying entirely exteriorly thereof, an extension arm secured to said lever to extend into said shaft, a keeper member adapted to be secured to a sliding door in fixed immovable relation thereto, said lever being biased to cause a part thereof to extend into the path of movement of said keeper, said keeper being movable into position to engage said contact actuator to close said contacts and to lie behind a part of said lever whereby such part of the lever prevents sliding movement of the keeper in one direction, said lever and extension arm being adjustable to reverse the bias thereof whereby said housing can be secured to either side of a door opening. 5
6. The combination of a housing adapted to be fastened to a door jamb of an elevator shaft, contacts within said housing, a contact actuator pivoted in said housing and having a part extending therefrom, a lever pivotally secured to said housing and lying entirely exteriorly thereof, an extension arm secured to said lever to extend into said shaft, a keeper member adapted to be secured to a sliding door in fixed immovable relation thereto, said lever being biased to cause a part thereof to extend into the path of movement of said keeper, said keeper being movable, upon closing of the door, into position to engage said contact actuator to close said contacts and to lie entirely behind a part of said lever, said keeper having a part thereof adapted to lie behind said part of the lever when the door is partially open, whereby further opening movement of the door is prevented. 10
7. The combination of a housing adapted to be fastened to a door jamb of an elevator shaft, contacts within said housing, a contact actuator pivoted in said housing and having a part ex- 15
- tending therefrom, a lever pivotally secured to said housing and lying entirely exteriorly thereof, an extension arm secured to said lever to extend into said shaft, a keeper member adapted to be secured to a sliding door in fixed immovable relation thereto, said lever being biased to cause a part thereof to extend into the path of movement of said keeper, said keeper being movable into position to engage said contact actuator to close said contacts and to lie behind a flat surface lying in the path of movement of the keeper in one direction and having a substantially flat surface lying in the path of movement of the keeper in the other direction, said keeper being movable into position to engage said contact actuator to close said contacts and to lie behind said flat surface whereby such surface of the lever prevents sliding movement of the keeper in one direction. 20
8. The combination of a housing adapted to be fastened to a door jamb of an elevator shaft, contacts within said housing, a contact actuator pivoted in said housing and having a part extending therefrom, a lever pivotally secured to said housing and lying entirely exteriorly thereof, an extension arm secured to said lever to extend into said shaft, a keeper member adapted to be secured to a sliding door in fixed immovable relation thereto, said keeper having a recess between the upper and lower edges thereof, said lever being biased to cause a part thereof to extend into the path of movement of said keeper, said keeper being movable into position to engage said contact actuator to close said contacts and to lie behind a part of said lever whereby such part of the lever prevents sliding movement of the keeper in one direction when the door is closed, said part of the lever being engageable in the keeper recess when the door is partially open to prevent further opening movement thereof. 25 30 35

BJARNE HENRICKSEN. 40
